UNITED STATES PATENT OFFICE.

GEORGE G. ALBERT, OF BANGOR, PENNSYLVANIA.

DESIGN FOR A METAL FITTING.

54,301.

Specification for Design.

Patented Dec. 23, 1919.

Application filed July 11, 1919. Serial No. 310,276. Term of patent 7 years.

To all whom it may concern:

Be it known that I, GEORGE G. ALBERT, a citizen of the United States, resident of Bangor, in the county of Northampton, State of Pennsylvania, have invented a new, original, and ornamental Design for a Metal Fitting, of which the following is a specification, reference being had to the accompanying drawing, forming a part thereof.

Figure 1, is a front elevation of a metal fitting showing my new design.

Fig. 2, is a top plan view thereof.

Fig. 3 is a bottom plan view.

I claim:

The ornamental design for a metal fitting, as shown.

GEORGE G. ALBERT.
